TOP WELL COVER

Edward E. Glowacke, Birmingham, Mich., assignor to General Motors Corporation, Detroit, Mich., a corporation of Delaware

Application June 6, 1957, Serial No. 46,510

Term of patent 7 years

(Cl. D14—27)

The portions of the automobile shown by means of broken lines are disclosed for illustrative purposes only.

I claim:

The ornamental design for a top well cover, substantially as shown and described.
